UNITED STATES PATENT OFFICE.

LOUIS J. TINT, OF CHICAGO, ILLINOIS.

MEANS FOR PROTECTING THE CONTENTS OF RECEPTACLES.

1,072,674.

Specification of Letters Patent.

Patented Sept. 9, 1913.

Application filed June 3, 1912. Serial No. 701,308.

To all whom it may concern:

Be it known that I, LOUIS J. TINT, a citizen of the United States, residing at Chicago, in the county of Cook and State of Illinois, have invented certain new and useful Improvements in Means for Protecting the Contents of Receptacles, of which the following is a specification.

My invention relates in general to receptacles, and more particularly to means for protecting the contents of receptacles from contamination through the ingress of impure or infected air.

When a portion of the contents of a receptacle is discharged, the remaining portion is exposed to infection from the impurities in the air which replaces the discharged portion of the contents. For this reason it is unsafe to use medicinal fluids, such as antitoxin, for instance, after they have been exposed to air, and hence any portion of the contents remaining after the receptacle is first opened is wasted. Various other fluids, such, for instance, as wines, must be entirely used when the receptacles containing them are opened, as any portions remaining in the receptacles soon become infected by the impurities in the air which replaces the discharged portions of the fluids.

The primary object of my invention is to provide means for preventing the air which replaces discharged portions of the contents of receptacles from infecting the contents remaining in the receptacles.

A further object of my invention is to provide means for automatically purifying the air which passes into receptacles to replace discharged portions of the contents of the receptacles.

A still further object of my invention is to provide an air inlet conduit for receptacles for purifying the air which passes into them, and which will be simple in construction, convenient in use, and efficient in operation.

My invention will be more fully disclosed hereinafter with reference to the accompanying drawing, in which an embodiment of my invention is illustrated in a perspective view.

Reference letter A indicates a receptacle for liquids, such for instance as a bottle.

B indicates a stopper for closing the mouth of the bottle A, which is preferably formed of rubber.

C indicates an air inlet conduit which ex-

tends through the stopper B into the interior of the receptacle A.

D indicates a chamber forming part of the conduit C and in which is placed suitable filtering or purifying material such, for instance, as sterilized cotton. The outer end of the conduit through which the liquid contents of the receptacle are discharged is preferably curved downwardly, as shown at d. The lower end of the conduit is preferably closed, and an opening c is provided through one wall thereof at a point within the receptacle below the stopper so that when the conduit is drawn outwardly through the stopper the opening c will be closed and the outlet sealed.

E designates an outlet conduit which extends upwardly within an opening extending partway through the stopper B.

F designates a syringe having a needle point f adapted to be forced through the portion of the stopper above the upper end of the outlet conduit E so that the contents of the receptacle may be drawn upwardly into the syringe. When the syringe is removed from the stopper the rubber of which the stopper is formed closes the opening made by the needle point above the outlet conduit E, so as to seal the receptacle against ingress of air. The thickness of the stopper above the outlet conduit is such that the material will tightly close the perforation made by the needle after it is removed, and will continue to successively close the opening after each insertion of the needle to remove portions of the contents of the receptacle. It is, therefore, unnecessary to provide any cap or plug to close the opening in the stopper through which the outlet conduit extends.

In the operation of this embodiment of my invention, the air inlet conduit is forced downwardly within the stopper until the opening c is exposed below the stopper. The needle inlet f of the syringe is then forced through the stopper B until its point lies within the upper end of the outlet conduit E. When the plunger of the syringe is drawn upwardly, liquid contents are drawn thereinto from the receptacle while air passes through the sterilized cotton in the chamber D into the receptacle to replace the withdrawn portion of its contents. The contents of the receptacle are consequently protected from infection by the impurities in the air, the air having been purified before passing into the receptacle.

From the foregoing description it will be observed that by means of my invention the contents of receptacles may be protected from contamination from impurities in the air which enters into the receptacles to replace the contents discharged therefrom, thereby rendering it possible to withdraw portions of the contents of the receptacles while the remaining portions of the contents are preserved against infection or deterioration. It will be further observed that my invention may be applied to receptacles of ordinary or usual form in common use.

15. I claim:

1. The combination with a receptacle having a discharge opening, of a removable stopper closing said opening, an air inlet conduit extending through said stopper 20 through which air passes into the receptacle to replace discharged portions of the liquid contents thereof, a chamber communicating with said conduit containing sterilizing material through which the air passes 25 to the interior of the receptacle, and a liquid discharge conduit supported at its upper end within a recess in the inner surface of said stopper, the portion of the stopper above said recess serving to normally close 30 said outlet against ingress of air and adapted to be pierced by the needle point of a syringe for withdrawing a portion of the liquid contents of the receptacle.

2. The combination with a receptacle having an opening, of a removable stopper closing said opening, an air inlet conduit extending through and adjustable relatively to said stopper, the lower end of said opening being closed, and an opening formed 40 therethrough adjacent the inner surface of said stopper through which air passes into the receptacle to replace discharged portions of the contents thereof, said conduit being

removable upwardly through said stopper to close said hole and seal the receptacle 45 when no contents are to be withdrawn therefrom, a chamber formed in said conduit containing sterilizing material through which air passes to the interior of the receptacle, a liquid discharge conduit supported at its upper end within a recess within the lower surface of said stopper, the portion of the stopper above said recess serving to normally close said outlet against the ingress of air and adapted to be pierced 55 by the needle point of a syringe for withdrawing a portion of the liquid contents of the receptacle.

3. The combination with a receptacle having a discharge opening, of a removable stopper closing said opening, an air inlet conduit extending through said stopper 60 through which air passes into the receptacle to replace discharged portions of the liquid contents thereof, a chamber communicating 65 with said conduit containing sterilizing material through which air passes to the interior of the receptacle, a liquid discharge conduit supported at its upper end within a recess in the inner surface of said stopper, 70 the portion of the stopper above said recess serving to normally close said outlet against ingress of air and adapted to be pierced by the needle point of an outlet conduit, and means for creating a difference in pressure 75 between the interior of the receptacle and said outlet conduit for forcing the liquid contents out of the receptacle and simultaneously replacing the discharged contents with sterilized air.

In testimony whereof, I have subscribed my name.

LOUIS J. TINT.
